UNITED STATES PATENT OFFICE.

MERRICK M. BARNES, OF BOSTON, MASSACHUSETTS.

PISTON-PACKING.

SPECIFICATION forming part of Letters Patent No. 767,728, dated August 16, 1904.

Application filed February 17, 1902. Serial No. 94,376. (No model.)

To all whom it may concern:

Be it known that I, MERRICK M. BARNES, a citizen of the United States, and a resident of Boston, in the county of Suffolk and State of Massachusetts, have invented certain new and useful Improvements in Piston-Packing, of which the following is a specification.

My invention relates to improvements in piston-packing; and its object is to produce a packing adapted especially to pack pistons working under high steam or other pressure.

In the drawings I have shown at Figure 1 in section a portion of the piston-head, which may be of any ordinary construction and to which my improvement is applied. In Fig. 2 I have shown in similar section a modified form of my improved device.

It will be understood that my improvement may be used in connection with the ordinary piston either with or without the bull-ring and follower, the novelty of the invention lying in the construction and arrangement of the packing-ring and its coacting devices.

Many forms of packing-rings heretofore in use have been expressly designed to increase the force with which the packing-ring is pressed against the cylinder-wall under a given working pressure in the cylinder, and a well-known means for accomplishing this result is the use of a wedge operated either by spring or cylinder pressure, or both, to increase the force with which the packing-ring is pressed outwardly. On the other hand, it has long been recognized by those familiar with the manufacture and use of piston-ring packing that when working under high pressures—say up to two hundred pounds or above—if the packing-ring is allowed to be pressed too tightly against the cylinder-wall it will produce excessive friction, wear out very rapidly, and also produce undue wear of the cylinder itself. My present invention is designed to provide a packing ring or rings especially adapted for use under high pressure and so designed that by means of wedge action the amount of outward pressure of the packing-ring against the cylinder-wall can be diminished with respect to the working pressure,

while at the same time insuring a tight joint and a long and even wear of the parts. To this end, I provide upon the rear wall of the packing-ring A, which may be of any suitable form adapted to be pressed outwardly by cylinder-pressure, a bevel or taper, and in connection with this ring I provide what I call a "restraining-ring" B. This is a ring placed in contact with the packing-ring A, preferably on the side away from the pressure and having its wall which is in contact with the tapered wall of the packing-ring correspondingly beveled or tapered, as shown. In the form of the device shown in Fig. 1 two packing-rings A A' are shown and also two restraining-rings B B', each pair being located in a groove in the bull-ring C.

By reason of the wedge construction of the parts A B it will be seen that an original pressure-tight fit of the packing against the bull-ring C and follower D can be obtained by lightly driving the ring B inwardly or toward the center of the piston. If now the device be put in use, it will be seen that the outward force of pressure upon the ring A will be restrained or in part be overcome by the pressure with which outward movement of this ring tends to force the ring B against the side of the groove in the bull-ring, so that the ring A will press against the cylinder-wall with less than cylinder-pressure. By varying the angle of bevel of the two adjacent faces of the packing-ring and restraining-ring it will be seen that the force with which the packing-ring is pressed outwardly and against the cylinder-wall may be varied with reference to the cylinder-pressure, thus insuring smooth running and long wear, while at the same time insuring a tight joint between the packing and the piston.

In the modified form shown in Fig. 2 I employ two packing-rings A A', but only one restraining-ring B', which ring has each of its faces adjacent to one of the packing-rings correspondingly beveled. A restraining-ring so constructed acting as a double wedge serves to press and hold both packing-rings tightly against the walls of the groove in the

piston-head or bull-ring and also to decrease the force with which each packing-ring is pressed out as cylinder-pressure is applied to it.

5 I claim—

The combination with a piston, of a packing-ring, movable outwardly under cylinder-pressure, and an outwardly-movable ring in beveled engagement with said packing-ring and 10 in frictional engagement with said piston,

whereby the pressure of said packing-ring against the cylinder-wall is lessened.

In testimony whereof I have hereunto subscribed my name this 15th day of February, 1902.

MERRICK M. BARNES.
